US00D670673S

(12) **United States Design Patent**
Roka

(10) **Patent No.:** **US D670,673 S**
(45) **Date of Patent:** **** Nov. 13, 2012**

(54) **MOBILE COMMUNICATIONS DEVICE WITH
HANDLE MEMBERS**

(75) Inventor: **Pujan K. Roka**, Atlanta, GA (US)

(73) Assignee: **Cox Communications, Inc.**, Atlanta, GA (US)

(**) Term: **14 Years**

(21) Appl. No.: **29/409,710**

(22) Filed: **Dec. 28, 2011**

(57) **CLAIM**

The ornamental design for a mobile communications device with handle members, as shown and described.

DESCRIPTION

FIG. 1 is a perspective view of a mobile communications device with handle members showing my new design;

FIG. 2 is a bottom view thereof;

FIG. 3 is a top view thereof;

FIG. 4 is a right side view thereof, the left side being a mirror image thereof; and,

FIG. 5 is back surface view thereof.

The broken lines are directed to environment and are for illustrative purposes only; the broken lines form no part of the claimed design.
